UNITED STATES PATENT OFFICE.

WALTER HAY, OF SEVILLE, OHIO, ASSIGNOR, BY MESNE ASSIGNMENTS, TO THE AUTOMATIC ADDRESSING MACHINE COMPANY, OF CLEVELAND, OHIO.

COMBINED PRINTING AND ADDRESSING MACHINE.

1,236,930.

Specification of Letters Patent. Patented Aug. 14, 1917.

Application filed December 29, 1910. Serial No. 599,932.

To all whom it may concern:

Be it known that I, WALTER HAY, a citizen of the United States, residing at Seville, in the county of Medina and State of Ohio, have invented a certain new and useful Improvement in Combined Printing and Addressing Machines, of which the following is a full, clear, and exact description.

This invention relates to machines for automatically printing mailing-addresses and the like upon a series of postal cards, envelopes, wrappers, statements and other objects from a series of independent and separate printing devices or addressing plates.

15 The primary object of the invention is to provide an automatic machine adapted to print a statement, advertisement, market quotations or other subject-matter upon one side of a series of cards or other objects and 20 at the same time to print mailing addresses upon the reverse side of such cards from a series of independent and unconnected addressing plates.

A further and important object of the invention is to provide a machine adapted to print as above described upon both sides of a card or other object, and at the same time to print an address upon one side of another card in one printing operation of the machine; in other words,—a machine in which 30 three printing impressions are made in one printing operation.

Other objects of the invention are to provide an automatic machine adapted to rapidly and positively move a number of separate addressing plates from a stack or supply into one or more printing positions and to deposit the addressing plates in a storing receptacle or file drawer after taking one or 40 more printing impressions therefrom; to provide a positive feeding mechanism and guiding means for the cards or other objects to be printed; to provide a simple and efficient mechanism for depositing the addressing plates in the file drawer; to insure proper inking of the printing devices; and the invention has other objects in view which will be pointed out hereinafter.

Machines adapted to print upon both sides 50 of a card or other object in one operation have been devised, in which the addressing plates are linked together in the form of a band or chain. For the purpose of more clearly pointing out commercial features of 55 improvement in the present invention, it

may be stated that all addressing machines which employ printing devices linked together in the form of a chain are rapidly becoming obsolete, being supplanted by machines using separate addressing plates. As 60 being mainly responsible for such substitution, the following objectionable features found in chain-type machines are cited: The chain or chains of printing devices, when not in use, are usually "rolled up," one printing 65 device resting upon another, which is apt to injure the faces of the type; and being stored in this form, it is quite inconvenient to make changes in certain addresses, to cancel others, and to make additions, especially in 70 alphabetical order; and it will readily be seen that these difficulties are greatly augmented when such machines are used for subscription lists, by large insurance companies, public service corporations, etc., 75 where the number of addresses extends into hundreds of thousands.

In contrast to the above described disadvantages, the present invention is closely associated with the most modern business 80 methods and comprehends, among other features, a series of indexed file-drawers in which the separate addressing plates may be stored in alphabetical order, and quickly and conveniently reached for purposes of reference and for making corrections, additions and cancellations.

Other meritorious features of the invention and details of construction will be fully understood from the following description 90 in connection with the accompanying drawings, forming a part of this specification, in which Figure 1 is a side sectional elevation of one form of a combined printing and addressing machine embodying the principles of 95 my invention, and taken at or near the longitudinal center of the machine; Fig. 2 is a diagrammatic plan view of the machine, the bed frame being omitted except as outlined by the dotted line; Fig. 3 is a front elevation largely sectional lengthwise of the runway along which the addressing plates are caused to travel; Fig. 4 is a slightly enlarged sectional view of the right hand end portion of Fig. 3, and shows the method of depositing 100 the addressing plates in the file drawer; Fig. 5 is a plan view of the printing platen, and its supporting and actuating members; Fig. 6 shows a clutch adapted to connect the two parts of the main shaft operatively together; 110

Figs. 7, 8 and 9 are detailed views relating to the feeding of the addressing plates; Fig. 10 is a perspective view of a file drawer adaptable to the machine, but not forming a part of this invention; Fig. 11 is a detailed view relating to the feeding of the cards or other objects to be printed, also to the carrier for main inking roll; Figs. 12 and 13 are different views of a card pusher; Fig. 14 is a perspective view showing the guiding means for the cards or other objects during their travel from the card magazine to the printing position; Fig. 15 is a perspective view of an addressing plate suitable for use in the form of machine here shown, but not forming a part of this invention; Fig. 16 is a front elevation showing the main inking roll and an automatic inking device for supplying the inking roll with ink; Figs. 17, 18 and 19 are detailed views of the inking device; Figs. 20, 21 and 22 illustrate samples of a large variety of work for which the machine is adapted, and are shown mainly to aid in describing certain functions of the machine.

Referring to the drawings, 1 is a bed frame adapted to be mounted in any suitable way, and removably secured to which is a magazine 2 (Fig. 3) of suitable dimensions to hold a supply of addressing plates A which by gravity pass through an opening in the bed frame to a runway 3 secured to and extending nearly the entire length of the bed frame which, at the end opposite the aforesaid magazine, is provided with an opening through which may be entered a file drawer B for receiving the addressing plates as they are discharged from the runway. A step-by-step movement of the addressing plates along the runway is effected by means of a reciprocating rod 4 journaled at one side of the runway and secured to which are a number of pins 5 equidistantly spaced slightly further apart than the length of the addressing plates. The rod 4 is reciprocated by means of a lever arm 6 (Fig. 2) pivotally secured at its rear end to the bed frame and actuated by a slotted cam 7 secured to the shaft 8 journaled in a number of hangers (one of which, 9, is shown in Fig. 6) secured to the bed frame; means for connecting the end of the lever arm 6 to the rod 4 consist of a split clip 10 (Figs. 8 and 9) loosely mounted on a reduced portion of the rod 4, and suitably secured to a holder block 11 constructed with a stud pin 12 passed loosely through one end of an adjustable link 13, the opposite end of which is pivoted to a grooved block 14 adapted for adjustment in a slot formed in the end of the lever arm 6 for the purpose of maintaining the proper longitudinal movement of the rod 4 as the cam 7 becomes worn; the purpose of the adjustable feature of the link 13 is to bring the addressing

plates into the proper printing position after the correct longitudinal movement of the rod 4 is obtained in the manner already described. The rod 4 is also subject to a rocking movement for the purpose of bringing the pins 5 into and out of engagement with the addressing plates; this rocking movement, approximately one-eighth of a revolution, is effected (see Figs. 2 and 7) by an oscillatory arm 15 suspended from the bed frame and provided at its lower end with a pin 16 carrying a cam roller 17 in the path of a cam 18 which cooperates with a spring 19 to give a reciprocating motion to a bar 20 pivotally connected at one end to the aforesaid pin 16 and at the opposite end to a crank 21 feather-keyed to the rod 4 which is permitted to slide (reciprocate) in the crank, but not to turn therein.

Also journaled in the runway, Figs. 1 and 2, in a horizontal plane with the rod 4 and at the side opposite thereto, is a companion rod 4^a carrying pins 5^a, and secured against longitudinal movement; this rod 4^a is adapted to be rocked by mechanism (part of which is shown in Figs. 2 and 7) at the side of and similar to that employed for rocking the rod 4, and for the like purpose of bringing the pins 5^a into and out of engagement with the addressing plates. It will be observed that the pins 5 and 5^a of the rods 4 and 4^a respectively rock, move or swing laterally in planes at right angles to the runway.

Referring to Figs. 1, 2 and 3, the method of feeding the addressing plates will now be described: When the rod 4 reaches its extreme right-hand position (Fig. 2) the pins 5^a of rod 4^a are lowered into a horizontal position before the pins 5 of rod 4 are raised to permit rod 4 to return; when rod 4 reaches its extreme left-hand position, its pins 5 are lowered into a horizontal position, and the one nearest the magazine end is in the clearance space X in position to move the lowermost addressing plate of a stack one step toward the printing position; the pins 5^a of rod 4^a are now raised to permit the advance stroke of rod 4 moving the addressing plate mentioned, and at the completion of this stroke, the pins 5^a are lowered, one at each end of the addressing plate which now occupies the first space from the magazine, for the purpose of securing the addressing plate against accidental longitudinal displacement; the pins 5 are now raised to permit the return stroke of rod 4, and so continuing; it being understood that as each addressing plate is moved from under the stack into the first space therefrom, the addressing plate that was in the first space will be moved into the second space, and so on; and it will be seen that the addressing plates are never free from engagement with both series of pins at one time,

which improvement insures positive and correct feeding.

Now referring to Fig. 3, it will be explained how the addressing plates, when leaving the runway, are deposited in a file drawer. As previously mentioned, B indicates a file drawer which has been inserted in an opening in the bed frame; oppositely and vertically disposed adjacent the open side of the file drawer are two parallel rods 22 (also see Fig. 2) having their upper ends secured to the bed frame, or they may otherwise be supported; adapted to slide up and down on rods 22 is a slide piece 23 constructed with a shelf 23' which is disposed in an inclined plane and extends into and nearly to the bottom of the file drawer, the end of the shelf next the bottom of file drawer being the higher as shown; secured to the slide piece 23 is a downwardly projecting extension 24 attached to the lower end of which is a cable 25 secured to and adapted to be wound on a drum 26 shaft-connected to a coiled band spring 27, the shaft to which the drum and spring are secured being journaled in a hanger 28 fast to the bed frame. Prior to the entrance of the addressing plates into the file drawer, and through the agency of the spring 27, the shelf 23' is normally held in its uppermost position against or close to a pair of oppositely disposed depressing blocks 29 secured to the inside of the file drawer and next the upper (front) end thereof; the bottom edges of these blocks are given an inclination opposite to that of the shelf, so that when the latter is against the blocks, a V-shaped space is formed. As the rod 4 pushes an addressing plate into the file drawer and into the V-shaped space, the file drawer remaining stationary, the addressing plate acts as a wedge and thus depresses the shelf, and this depression continues until (see Fig. 4) the addressing plate has been pushed beyond the end of the runway, at which point the end lastly on the runway is caused to fall onto the shelf, the fall being sufficient to provide unobstructed passage for the forward end of the next addressing plate which, during its progression, enters as a wedge between the depressing blocks and the first addressing plate, thus depressing the latter and finally falling into proper position in the file drawer to make room for the next addressing plate, and so on. It will be understood that as the weight of addressing plates on the shelf increases, the tension of the spring 27 also increases proportionately, hence the initial upward pressure of the shelf against the depressing blocks is substantially maintained in the case of each succeeding addressing plate as it is borne against the depressing blocks; also that when a file drawer is withdrawn, the shelf, through the action of the spring, will rise

therewith until stopped by suitable means at its uppermost and initial position.

Now referring to Fig. 1, the present and preferred construction employed for printing and addressing will be described: Secured to the bed frame is a downwardly and rearwardly projecting bracket 30, to the lower end of which is pivotally connected a lever arm 31 oscillated in a vertical plane by means of a cam-arm 32 secured to the shaft 8' which is in line with and is designed to be clutched to the shaft 8, as will be explained more fully, and provided with a cam-roller 33 which enters an aperture in the lever arm so formed that an up-and-down movement will be imparted thereto, during one half revolution of the shaft, and during the other half of the revolution the lever arm will remain motionless. Oppositely disposed and secured to the top of the bed frame are two upright frame pieces 34 (also see Fig. 5) each provided with a stud pin 35 loosely mounted upon which is a bifurcated lever 36 in operative connection with the aforesaid lever arm 31 through a connecting link 37. The front end of the lever 36 is pivotally connected to the upturned ends of a platen holder 38 by means of stud-pins 39, vertically above which and separated somewhat therefrom are stud pins 40 secured to the upper extremities of the platen holder; secured to the frame pieces 34 and vertically above stud pins 35 are stud pins 41 which together with stud pins 40 are loosely passed through opposite ends of a connecting link 42; the distance between the centers of pins 41 and 40 being the same as between pins 35 and 39, and the vertical distance between the centers of pins 35 and 41 being the same as between pins 39 and 40, it will readily be understood that the well known principle of parallel motion is employed in the present invention, and that it is admirably adapted to maintain the base of the platen holder in a horizontal position throughout its entire stroke, and at the same time lateral movement is prevented in the simplest possible manner by means of the bifurcated lever. Projecting through the base of the platen holder and near the sides thereof are four adjusting screws 43 distributed in pairs near each end of the base; two clamping screws 44 are passed centrally through the base, one at each end and a little outside of the adjusting screws, as shown: these clamping screws are each provided at their lower ends with a head and at the upper ends with a screw thread adapted to receive a nut 45; by means of the screws as thus arranged, a platen 46 is removably secured to the platen holder, and obviously adapted to reliable adjustment to bring the printing device carried thereby into parallel position relative to the surface of the bed frame. As shown, a rubber stamp C is se-

cured to the platen, but instead of this arrangement a chase for holding type, or an electrotype, or any other device or combination of devices used for printing may be employed and secured by means of the before-described screws to the platen holder.

Positioned beneath and well toward the front of the bed frame and journaled in suitable hangers (not shown) secured thereto 10 is a rock shaft 47 (also see Fig. 2) to which are secured forwardly projecting arms 48 provided at their forward ends with adjusting screws 49 adapted to contact with vertically movable plungers 50 and 51 (also 15 see Fig. 3) to the upper end of each of which is secured a rectangular platen 52; as shown, the plungers are arranged transversely central of the runway and are adapted to move therein, and each is formed with an enlarged 20 portion at the lower end forming a shoulder, pressing downwardly against which is a spring 53; it will be seen in Fig. 1 that the addressing plates are free to travel over and past the platens, and also that when the latter 25 are raised, the addressing plates directly over said platens are adapted to be raised thereby. Secured to the intermediate portion of the rock shaft 47 is a rearwardly projecting arm 54 arranged in the path of a cam roller 55 carried by a cam-arm 56 secured to the shaft 8'.

From the foregoing it will be seen that the arm 54 is depressed and the plungers raised by the cam action and that the plungers 30 will be depressed and the arm 54 raised into the path of the cam roller by the springs 53. The cams which actuate the lever arm 31 and the arm 54 are so timed that the printing device secured to the platen holder 35 will be moved to its lowermost position simultaneously with the raising of the platens 52 into their uppermost positions. Directly above the plungers 50 and 51 are openings 1^a and 1^b, in the bed frame 1 of 40 sufficient size as to permit the entrance therethrough of the upper portion of the addressing plates; secured to the upper side of the bed frame and extending across the opening 1^b above the plunger 51 is a plate 57 (Fig. 45 3) having its forward portion raised somewhat from the bed frame so as to permit the insertion of a card, or other object to be printed, between the two.

The movement of the cards to the printing 50 position and the inking of the printing device C are effected by means of the following described movement: A slide plate 58 (Figs. 1 and 11) is centrally mounted on a transversely arranged rod 59 secured at 55 each end to the bed frame, and is steadied by its overhanging ends being in contact with bearing surfaces formed on the lower side of the bed frame; thus providing a three-point bearing, as plainly shown in Fig. 11; the slide-plate, where it is support-

ed by the rod 59, is constructed with grooved lugs 60 which prevent lateral displacement. The slide plate is reciprocated in a horizontal plane by a link 61 (Fig. 2) connected to the longer arm of a bell crank lever 62 pivotally connected to the bed frame and provided at the end of its shorter arm with a cam roller 63 which enters the slot of a cam 64 secured to the shaft 8' and so formed as to effect a complete forward and return movement of the slide plate during one half revolution of the shaft. Secured to each end of the slide plate is a standard 65 which projects upwardly through a slot in the bed frame and has secured to its upper end a forwardly projecting flexible arm 66; these arms are formed with a U-shaped depression or bearing at their front ends in which an inking roll 67 is supported and adapted to rotate. A pair of card pushers 68 are also secured to the slide plate and project upwardly and forwardly through slots in the bed frame; Figs. 12 and 13 show a plan and side elevation of one of these card-pushers, which are preferably made of spring material and mounted on blocks 68^a adapted for adjustment in grooves formed in the slide plate; a slot 68^b through which a screw is passed provided adjustment to suit various widths 90 of cards, or other objects to be printed. As shown, the card pushers are provided with pushing members 68^c and a central gage tongue 68^d, which projects somewhat beyond the pushing members and is depressed therefrom to an extent approximating three quarters of the thickness of a card, envelop, etc., to be printed; in operation, the gage tongue is caused to bear against the underside of a card, and to act as a gage to prevent the pushing members from engaging more than one card at a time; during the return movement of the slide plate, the forward ends of the card-pushers are depressed by the weight of the stack of cards, under which they slide, and this depression continues until the pushing-members have reached the rear edge of the lowermost card, at which point they will spring upwardly into position to engage and move the card, the gage-tongue 105 limiting the upward movement so as to prevent engagement with the second card above, as will be seen in Fig. 13, it being understood that the gage-tongue is not permitted to slide past the card at the end of the return stroke. It will be understood that instead of making these card-pushers of 110 spring material, they can be made of more rigid material, and the principle of their operation still be retained.

Referring to Fig. 1, a magazine 69, adapted to hold a stack of cards, envelops, or any other objects to be printed, is secured to the bed frame at the rear and out of the path of the platen 46; along the bottom of the 115

front side of the magazine a space or slot is provided through which the cards may successively be pushed, and adjustably secured to the magazine above this space is a 5 gate or gage piece 70 adapted for vertical adjustment and to prevent the egress of more than one card at a time.

As the cards come from the magazine, they are caused to enter between and under 10 a pair of guide-bars 71, Fig. 14, formed with side walls 71^a, which extend below the surface upon which the cards are supported and which guide the cards laterally, and with overlying portions 71^b adapted to rest 15 or bear upon the end portions of the cards for the purpose of preventing one card from "climbing" upon another. The guide bars are kept in their proper positions, which is governed by the size of the cards or other 20 objects to be printed, by means of four screws 72 loosely passed through the guide bars and adjustably secured to the bed-frame; ordinarily the weight of the guide bars will be sufficient to hold the cards in 25 place, but failing in this, helical springs can be interposed between the heads of the screws and the guide-bars to insure the requisite pressure. It should be understood that a card coming from the magazine into 30 the printing position is employed to push the printed card out of the way.

As shown in Fig. 1, the automatic inking device is supported by the card magazine and operated by one branch of the bifurcated lever 36. However, it may be supported and operated in any other suitable manner. Its construction comprises a frame 35 73 (also see Fig. 16) constructed with forwardly-projecting end-portions in which is journaled a distributing roll 74 adapted to be rotated by a pinion 75 enmeshed with a gear 76 rotated through part of a revolution by a lever 77 (Fig. 17) provided at its forward end with a roller 78 arranged in the 40 path of one branch of the bifurcated lever 36, which during its downward stroke depresses the forward portion of the lever and raises the rear portion thereof to which is pivotally connected a pawl 79 arranged to 45 engage with the teeth of the gear 76; the latter and the lever 77 are loosely mounted on a common axle secured to the frame 73, and as the bifurcated lever 36 is being returned to its uppermost position, the lever 50 77 will follow by reason of its rear end being weighted, the pawl 79 slipping past the gear-teeth in its descent, as will be clearly understood from the drawings. Superimposed on the distributing roll and extending 55 nearly the entire length thereof is an ink reservoir 80 constructed with a centrally-located tank 80^a and up-turned ends 80^b and 80^c provided with stud pins 80^d which project through vertical slots formed in the 60 ends of the frame 73, (see Fig. 18); the 65

end 80^c of the reservoir is also provided with a second stud pin 80^e located vertically above and separated somewhat from the stud-pin 80^d, the upper stud pin projecting beyond the frame end to receive the thrust of a pivoted arm 81 which thrust is exerted by a spring-actuated plunger-pin 82 inserted through an adjusting screw 83 carried by the frame-end. It will be understood by referring to Fig. 19, that when the distributing-roll is rotated through all or part of a revolution, the ink reservoir will be rocked by friction caused by its weight being supported by the distributing roll; and that the extent of the rocking motion 70 will be regulated by the adjusting-screw 83. The bottom of the ink reservoir is provided with a slot extending nearly the entire length thereof and adapted to be filled with ink through the medium of a hole communicating with the bottom of the tank, which hole may be closed by a valve-plug. When the ink reservoir is rocked in the manner already described, the slot therein will be opened next the distributing roll, and thus 75 permit ink to run thereon; and when the rotation of the distributing roll ceases, the ink reservoir will be returned to its normal, upright position by means of the spring-exerted arm 81, the ink between the distributing roll and reservoir serving as a lubricant to assist the return. If a surplus of ink is delivered to the roll, the friction between the roll and reservoir will be lessened thereby, and in proportion as such 80 surplus of ink acts as a more effective lubricant, consequently the reservoir will not be rocked as much, and a lesser amount of ink will be delivered. The inking roll 67, when 85 in its rearmost position, is in operative contact with the distributing roll and is rotated and inked thereby. 90

In Fig. 1, W indicates a weight which is adjustably secured to the rear portion of the lever arm 31, to cause equilibrium of the 95 various parts in operative connection therewith, and hence to effect smooth running of the machine.

In Fig. 2, S indicates a sprocket wheel which is secured to the shaft 8 and rotated 100 by any suitable means, such as a treadle arrangement or some form of motor.

There are various ways in which the addressing plates may be held in the file drawers when the latter are in a vertical position, and released therefrom when inserted in the magazine 2. One method is shown in Fig. 10, in which B' indicates a pair of oppositely-disposed yieldable retainers secured at one end to the outsides of the file drawer and 105 having their opposite ends bent inwardly so as to partly close the open end thereof; the retainers are formed near their bent ends with L-shaped projections B² which, when 110 the file drawer is inserted in the magazine 2, 115

are adapted to be engaged by vertically-disposed angle-bars, (not shown), arranged one at each side in the magazine and in such manner as to permit their being spread 5 apart and so held during the withdrawal of the file drawer, the retainers being likewise spread apart thereby so as to unobstruct the end of the file drawer.

In considering the arrangements of parts 10 and the operation of the machine as thus far described, it is apparent that were the entire machine operated at the start, three cards would be moved out and away without being printed on their lower sides, by reason of 15 four revolutions of the machine being required before the first addressing plate arrives at the central printing position. And it should be stated that there are occasions when it is not desired to print from certain 20 addressing plates, hence it will be obvious that in such cases the printing and card feeding mechanisms should be stopped until such addressing plates have been moved past the printing position.

25 To properly provide for the above conditions, I employ what may be termed a cut-out mechanism shown in Fig. 2, and comprising a push-rod 84, to the front end of which is secured a push-button 85, the rear 30 end being pivotally connected to a bell-crank lever 86, pivotally connected to a bracket (not shown) secured to the bed-frame; this lever, as shown, is formed with a rearwardly projecting portion which terminates in a yoke apertured to receive the pins of a clutch-ring (not shown) loosely mounted on the slidable part of a clutch 87 (Fig. 6), feather-keyed to the shaft 8' having its inner end journaled in the fixed part 35 of the clutch 87^a, keyed or otherwise firmly secured to the inner end of the shaft 8; one part of the clutch is formed with a single jaw, and the other part with a single depression to receive the jaw. Therefore, 40 whenever the two shafts are clutch-locked together, virtually forming one continuous shaft, the various mechanisms will be in correct time with each other. And the mechanism which feeds the addressing 45 plates being the only one operated by the shaft 8 which is directly connected with the driving means, it will be seen that when the shafts are unclutched, the printing and card-feeding mechanisms will be put out of 50 action.

The practical operation of the machine will now be briefly described. A series of cards or other objects to be printed are placed in the card magazine, and a file 55 drawer containing addressing plates is inserted in the magazine provided for this purpose and the addressing plates released from the file drawer which is then inserted through the opening at the discharge end 60 of the runway; the push-button 85 is then

pushed in and the machine started, the mechanism feeding the addressing plates being the only one in action. As the addressing plates are moved step by step from their magazine, to the printing position or positions 70 they are caused to be inked by some suitable form of inking device, (one form being shown in Fig. 3, and indicated by the numeral 88). As the first addressing plate comes into the first printing position, an 75 opening in the bed frame permitting observation, the push-button is released and the shaft 8' with its associated mechanisms permitted to come into action. A card or other object to be printed is then pushed 80 into the printing position simultaneously with the inking of the printing device C by the inking roll 67. Immediately following the retraction of the slide-plate carrying the inking roll, the printing device C is brought 85 down upon the card simultaneously with the raising of the addressing plate against the under side of the card, and simultaneously also with the return stroke of the reciprocating rod 4. The upper and lower 90 printing devices are then moved to their respective uppermost and lowermost positions; another card is then moved out from the card magazine to the printing position as the inking-roll is moved across the upper 95 printing device, and as the second addressing plate is being brought into the printing position; the inking roll is now retracted and reaches its rearmost position at or about the same time that the addressing plate 100 comes to rest in its printing position. The upper and lower printing devices are then brought together, being separated only by the card or other object which receives an impression from both simultaneously or substantially so, and the operations thus continuing until the last addressing plate in the magazine has been printed from, immediately following which the push button is 105 again pushed in, thus permitting the clearing of the runway and the depositing of the used addressing plates in the file drawer while the printing and card feeding mechanisms are out of action.

When it is not desired to print from one 110 or more addressing plates, and before such are permitted to enter the printing position, the push button is pushed in, which, as before explained, puts the printing and card feeding mechanisms out of action until 115 such addressing plates have passed beyond the printing position, when the push button is released and the printing continued.

In Fig. 20 is shown a modern form of statement similar to that used by certain 120 public service corporations and printed on the reverse side of a standard U. S. postal card, such visible statements now being permitted to pass through the mails. At or about the same time the statement form (ex- 125 130

cluding the address shown at one end) is being printed in the herein-described machine, an address is being printed on the obverse side of the card by an addressing plate and which obverse side is shown in Fig. 21. At or about the time the addressing plate from which this address was printed reaches the second printing position, (above plungers 51, Fig. 3), the card is inserted between plate 57 and the bed frame and receives a second impression from the same addressing plate, (this address being shown at one end of the card in Fig. 20), simultaneously, or substantially so, with the printing on both sides of another card in the first or central printing position of the machine. Thus it will be seen that the machine is adapted to print two cards or other objects and make three printing impressions in one printing operation. As showing the utility of the repeated address on the reverse side of the card, it may be stated that when the statement is received, the end of the card containing the repeated address is detached, and this stub end serves as a memorandum to show that the addressee has paid.

Fig. 22 shows one of many forms of modern advertising adapted to be printed by the machine herein described. In this case, the invitation is made more effective by having the address repeated above the salutation, it being understood that the address is first printed on the obverse side of the card.

It is obvious that the addressing plates are deposited in the file drawers in the same order in which they come out, and that they are adapted to be arranged therein in accordance with a card-index system, the indices appearing at the upper ends and being readily seen when the addressing plates are stored in the file drawers, which latter are also adapted to be indexed in accordance with the most modern methods. In Fig. 15, the type carried by the address plate for printing the name and address are designated *a*, and the index characters on the plate are designated *a*¹.

It should be distinctly understood that I do not in any way restrict this invention to a construction adapted for or to its use with the addressing plates shown, as obviously various styles of and much thinner addressing plates could be used, and moving and locking members of any suitable form could be secured to rods 4 and 4^a.

Without limiting myself to the exact construction and arrangement of parts herein shown and described, what I claim and desire to secure by Letters Patent is:

60 1. In a printing and addressing machine, the combination of a magazine for holding a series of separate addressing plates or printing devices, a runway arranged to receive said printing devices from the magazine, and a means reciprocable lengthwise

of the runway and rockable about an axis extending longitudinally of the runway for engaging and moving the printing devices along the runway, from the magazine to printing position.

2. In a printing and addressing machine, the combination of a magazine for holding printing devices, a runway arranged to receive said printing devices from the magazine, a receptacle positioned at the end of the runway opposite the magazine, and means reciprocable lengthwise of the runway and rockable about an axis extending lengthwise of the runway for engaging and moving the printing devices along the runway from the magazine to and beyond printing position.

3. In a printing and addressing machine, the combination of a magazine for holding printing devices, a runway arranged to receive said printing devices from the magazine, means movable lengthwise of the runway for moving the printing devices spaced apart along the runway from the magazine to printing position, and also movable laterally in planes at right angles to the runway for engaging and disengaging the printing devices, and means for securing the printing devices against displacement when they are disengaged from the moving means.

4. In a printing and addressing machine, the combination of a magazine for holding printing devices, a runway arranged to receive said printing devices from the magazine, a device having means for engaging the printing devices and reciprocatable in the direction of its axis to move the printing devices along the runway and rockable about its axis to cause said means to engage and disengage the printing devices, and means for holding the printing devices against displacement when disengaged from the said means.

5. In a printing and addressing machine, the combination of a magazine for holding printing devices, a runway arranged to receive said printing devices from the magazine, reciprocatable means for engaging and moving the printing devices spaced apart along the runway from the magazine to printing position, said means being also movable laterally in planes at right angles to the runway to engage and disengage the printing devices, and means for securing the printing devices against displacement when they are disengaged from the reciprocatable means.

6. In a printing and addressing machine, the combination of a magazine for holding printing devices, a runway arranged to receive said printing devices from the magazine, a receptacle positioned at the end of the runway opposite the magazine, reciprocable means for moving the printing devices along the runway from the magazine

to and beyond the printing position and into the receptacle, said means being also movable laterally in planes at right angles to the runway to engage and disengage the printing devices, and means for securing the printing devices against displacement when they are disengaged from the reciprocatable means.

7. In a printing and addressing machine, 10 the combination of a magazine for holding printing devices, a runway arranged to receive said printing devices one by one from the magazine, means reciprocatable in the direction of its longitudinal axis and rockable about said axis and provided at intervals lengthwise thereof with devices for engaging and moving the printing devices step by step and spaced apart along the runway.

8. In a printing and addressing machine, 20 the combination of a magazine for holding printing devices, a runway arranged to receive said printing devices one by one from the magazine, means adapted to engage and disengage printing devices for moving the latter along the runway step by step, and means provided at intervals lengthwise thereof with devices adapted to be projected between the printing devices for engaging and holding the printing devices in the runway against displacement when out of engagement with the moving means.

9. In a printing and addressing machine, the combination of a magazine for holding printing devices, a runway arranged to receive said printing devices one by one from the magazine, reciprocatable means provided at intervals lengthwise thereof with devices for engaging and moving the printing devices step by step and spaced apart along 35 the runway, and movable means provided at intervals lengthwise thereof and fixed thereto with devices for engaging and locking the printing devices against displacement when they are disengaged from the reciprocatable 40 means.

10. In a printing and addressing machine, the combination of a magazine for holding printing devices, a runway arranged to receive said printing devices one by one from the magazine, a rod provided at intervals lengthwise thereof with pins and adapted to be rocked to bring the pins into and out of engagement with the printing devices and also to be reciprocated to move the printing 50 devices step by step along the runway, said pins also serving to space the printing devices apart.

11. In a printing and addressing machine, the combination of a magazine for holding 60 printing devices, a runway arranged to receive said printing devices one by one from the magazine, a pair of rods disposed lengthwise of the runway and provided at intervals along their length with pins, one of said

rods adapted to be rocked to bring its pins 65 into and out of engagement with the printing devices and also to be reciprocated to move the printing devices step by step along the runway, and the other of said rods adapted to be rocked to bring its pins into 70 and out of engagement with the printing devices for the purpose of locking same against displacement during the return stroke of the first mentioned rod and while its pins are disengaged from the printing devices. 75

12. In a printing and addressing machine, the combination of a magazine for holding a series of separate printing devices, a bed frame having a plurality of apertures, means for moving said printing devices step by 80 step along the bed frame from the magazine to a plurality of printing positions opposite said apertures, and means for causing a plurality of printing devices to be inserted through the apertures of the bed frame and 85 devices opposite the apertures and co-operating with the last named means so as to cause the printing devices to print on one side of a plurality of objects in one printing operation of the machine. 90

13. In a printing and addressing machine, the combination of a magazine for holding a series of separate printing devices, a bed frame having a plurality of apertures, means for moving said printing devices step by 95 step along the bed frame from the magazine to printing positions in registration with said apertures, and reciprocatable members arranged also in registration with the apertures for causing the printing devices in 100 printing positions to be simultaneously inserted through said apertures and means opposite the apertures for co-operating with the reciprocatable members to cause the printing devices to make a plurality of impressions 105 at one printing operation of the machine.

14. In a printing and addressing machine, the combination of a magazine for holding a series of separate printing devices, a bed frame having a plurality of apertures, means for moving said printing devices step by step along the bed frame from the magazine to the apertures through which the printing devices may be inserted, reciprocatable devices below the apertures of the bed frame for causing a plurality of printing devices to be raised through said apertures, a printing device above one of the apertures, an abutment above the other aperture, and means for actuating the printing device and the reciprocatable means so as to print on both sides of one object and on one side of another object at one printing 115 operation of the machine. 120

15. In a printing and addressing machine, the combination of a magazine for holding a series of separate printing devices, a bed having a plurality of spaced apertures there- 125

- in, a plurality of reciprocatable devices arranged beneath said apertures, a printing member above one of the apertures, an abutment above a second aperture, means for feeding the separate printing devices step by step along the bed beneath said apertures, and means for actuating the printing member above the bed and for raising the reciprocatable devices below the bed so as to cause the printing devices directly above the reciprocatable devices to be raised and inserted through said apertures, so as to cause three printing impressions to be made at one printing operation.
16. In a printing and addressing machine, the combination of a receptacle for holding a series of objects to be printed, a slide piece reciprocatable beneath the objects to be printed, means connected to said slide piece for engaging and moving said objects to printing position, a printing member, a reciprocatable inking device connected to the slide piece and movable with the same for inking said printing member, and means for reciprocating the slide piece.
17. In a printing and addressing machine, the combination of an upper movable printing member, means for moving, step by step, a plurality of separate printing devices beneath said upper printing member, automatically actuated means for moving a blank to be printed to printing position beneath said upper printing member, means for inking the upper printing member, and means for actuating the feeding means for the printing devices, the feeding means for the blanks and the inking means so that the feeding of the printing devices and blanks and the inking of the upper printing member take place simultaneously.
18. In a printing and addressing machine, a bed, a main printing member for printing the same subject matter on a plurality of blanks, a magazine for containing a plurality of separate printing devices, each adapted to print on a blank, mechanism for feeding the printing devices from the magazine along the bed to and beyond printing position, mechanism for causing the main printing member and said printing devices to print on the blanks, and manually operable means for at will stopping the printing operations without affecting the feeding of said printing devices.
19. In a printing and addressing machine, a bed, a vertically reciprocatable printing member for printing the same subject matter on a number of blanks to be printed, a magazine for containing a number of separate printing devices each adapted to print on a blank, mechanism for feeding the printing devices step by step along the bed and for causing said printing member and printing devices to make printing impressions on the blanks, and manually operable means for at will stopping the printing of said printing member and printing devices without affecting the feeding of the latter.
20. In a printing and addressing machine, a bed, a magazine for holding a series of separate printing devices, each adapted to print on one side of a blank, means for feeding the printing devices step by step along the bed, a reciprocatable printing member for printing the opposite side of the blanks, mechanism for causing the reciprocatable printing member and printing devices to make printing impressions and for causing the actuation of said feeding means for the printing devices, and manually operable means for at will stopping the printing operations without affecting the feeding of said printing devices.
21. In a printing and addressing machine, a bed, a magazine for holding a series of separate addressing devices, means for feeding said devices along the bed, a vertically reciprocatable printing member for printing on one side of blanks to be printed, means for actuating said printing devices one at a time so as to print on the other side of the blanks, a receptacle for holding the blanks, means for feeding the blanks one at a time from the receptacle to printing position, and manually operable means for at will stopping the operation of the printing member and of the blank feeding means without affecting the operation of the feeding means of the printing devices.
22. In a printing and addressing machine, a bed, a printing platen, a holder for said platen, means for reciprocating the holder and for causing the platen to be maintained in parallelism with the bed comprising a parallel movement mechanism including a lever and a link both connected to the holder and to the bed, and mechanism for actuating the lever, the lever being pivoted intermediate its ends, and connected at one end to said holder and at its opposite end to said actuating mechanism.
23. In a printing and addressing machine, a bed, a printing platen, a holder therefor, means for reciprocating the holder and for causing the printing platen to be maintained in parallelism with the bed comprising a parallel movement mechanism including a bifurcated lever, and links parallel thereto, the lever and links being pivotally connected to the holder and to the bed at points equidistant apart, and mechanism for actuating said lever, the lever being pivoted intermediate its ends, and connected at one end to said holder and at its opposite end to said actuating mechanism.
24. In a printing and addressing machine, a bed, a magazine at one end of the bed adapted to contain a plurality of sepa-

rate printing devices, a receptacle at the opposite end of the bed, means for feeding the printing devices from the magazine to and beyond printing position and into the receptacle, a yieldable and vertically movable support in said receptacle and adapted to sustain the printing devices as they are deposited therein, and tapered depressing members at the upper end of the receptacle 10 adapted to be engaged by the printing devices as they are moved into the receptacle, so as to force the printing members already deposited therein downward.

25. In a printing and addressing machine, a bed, a magazine at one end of the bed adapted to contain a plurality of separate printing devices, a receptacle at the opposite end of the bed, means for feeding the printing devices from the magazine to 15 and beyond printing position and into the receptacle, a yieldable and vertically movable support in said receptacle and adapted to sustain the printing devices as they are deposited therein, tapered depressing members 20 at the upper end of the receptacle adapted to be engaged by the printing devices as they are moved into the receptacle, so as to force the printing members already deposited therein downward, and means for 25 maintaining a substantially constant upward pressure of said support as the printing devices are successively deposited thereon.

26. In a combined printing and addressing machine, a bed, a magazine at one end of the bed adapted to receive a plurality of separate printing devices, a receptacle at the opposite end of the bed, means for feeding the printing devices along the bed from 30 the magazine to and beyond printing position and into the receptacle, a support in the receptacle for the printing devices, said support being vertically yieldable and provided with an inclined upper face, and inclined depressing members at the upper 35 end of the receptacle inclined oppositely with respect to the upper face of the support, whereby the printing devices entering between the support and said depressing members will have a wedging action to 40 lower the support and printing devices already deposited in the receptacle.

27. In a printing machine, a bed, a printing platen, means for actuating the platen, 45 an inking roller adapted to engage said platen when elevated, an ink distributing roller adapted to engage the inking roller, an ink reservoir arranged above said distributing roller and having a discharge 50 orifice, and means for rocking said reservoir during the actuation of the platen so that ink may pass from said reservoir onto the ink distributing roller.

28. In a printing machine, a bed, a mov-

able printing platen, means for actuating 65 said platen, an inking roller adapted to be moved over the face of the platen when elevated, an ink distributing roller adapted to engage the inking roller, a rockable reservoir having a discharge orifice normally sealed 70 by said distributing roller, and means for rocking said reservoir and for simultaneously turning said distributing roller during the actuation of the platen.

29. In a printing machine, a bed, a printing platen, means for actuating the platen comprising a pivoted lever, an inking roller adapted to be moved over the face of the platen, an ink distributing roller adapted to engage the inking roller, a rockable reservoir 80 arranged above the distributing roller and provided at the bottom thereof with an elongated orifice normally sealed by the distributing roller, and mechanism actuated by said lever during the actuation of the platen 85 for turning the distributing roller, and rocking said reservoir so as to open the orifice.

30. In a combined printing and addressing machine, a bed plate and a platen therein provided with an opening and adapted to support a card to be printed, a vertically reciprocable plunger over the platen, a vertically reciprocable plunger underneath said platen, an upper type holder attached to said upper plunger, a movable lower type 95 holder adapted to rest upon the lower plunger, a common actuating shaft for both plungers, and mechanism operatively connecting both said plungers and said shaft whereby said plungers move simultaneously 100 toward said card to print said card simultaneously on opposite sides and means for retaining the type holders on said plunger while the impression therefrom is being made.

31. In a combined printing and addressing machine, a bed plate and platen therein having a printing opening, plungers adapted to move toward and from said platen on opposite sides thereof, a common operating 110 shaft, mechanism operatively connecting said plungers and shaft, type for one plunger, movable type holders for the other plunger, means for feeding a succession of said movable type holders to said plunger, means for retaining them on said plunger while in the printing position, and means for applying ink to the type in each type holder before the impression is made.

32. In a printing and addressing machine, 120 in combination, a platen, vertically moving plungers one above and one below the platen, a type holder adjustably secured to the upper plunger, said lower plunger adapted to raise in turn a series of movable lower type 125 holders, a guide for the movable type holders, a reciprocating device for propelling said type holders in said guide and adapted

to alternately engage and release said type holders, mechanism for operating said reciprocating device, means for locking said type holders on said plunger in the printing 5 position and when the said reciprocating device releases them, and operating means for said plungers, and for said propelling and locking devices.

33. In a combined printing and addressing machine, plungers adapted to reciprocate simultaneously in opposite directions, and an intermediate platen having a printing opening, a series of movable type holders, a device for feeding said type holders in 10 succession to a printing position opposite the opening in said platen, means for locking the movable type holders on said plunger when in the printing position, a card receptacle for cards to be printed, means for feeding the cards to be printed to said platen, means for operating the plungers simultaneously and for operating the card feeding means when the plungers retire from the platen.

34. In a machine for the purpose described, in combination a bed plate, a platen therein having a printing opening, a card receptacle on said bed plate, upper and lower plungers, mechanism for reciprocating 15 the plungers simultaneously in opposite directions, mechanism for feeding the cards one at a time from the receptacle, a common operating shaft, mechanism operatively connecting the shaft, plungers and card feeding mechanism, reciprocating mechanism for feeding movable type holders to the lower plunger one at a time, means thereon for alternately engaging and releasing said type holders as said feeding mechanism reciprocates, mechanism for locking the type 20 holders on said plunger while the action of printing occurs, and for thereafter releasing them, and means operatively connected with said shaft for operating said locking 25 means.

35. In a machine for the purpose described, a bed plate, a type holder guiding channel therein, a reciprocating rod pivoted in said bed plate and provided with engaging 30 means for said type holders, a main shaft, a cam thereon, a rock arm engaging said shaft and pivoted rod respectively, a second cam on said shaft, an arm on said rod, and intermediate mechanism operatively connecting said arm and cam whereby said rod is rocked on its axis, at the end 35 of its stroke in each direction to alternately

engage and disengage said type holder engaging devices.

36. The combination of a bed plate having 60 an opening, a platen thereon having a printing opening, a channel guide in said bed plate for type holders, passing underneath said platen, a rocking rod pivoted on each side of said channel guide, each rod provided with type holder engaging means, one of said rods reciprocating, a main shaft, a cam thereon, and rock arm adapted to reciprocate said reciprocating rod, an additional cam thereon for each rod, and means operatively connected therewith for rocking said 65 rocking rods at predetermined relative periods of time, and means for returning the rods to their initial positions.

37. In a printing and addressing machine, 70 a base plate, a receptacle for blanks, a platen or blank supporting member arranged in front of the receptacle and having an opening therein, a main printing device arranged over the platen and adapted to be moved 75 toward and away from the same, a hopper adapted to be supplied with slugs arranged at the side of the platen, a guideway in the bed plate extending laterally from the hopper toward and in line with the platen, a 80 slug lifting device arranged below the platen adapted to be moved toward and away from the same, a reciprocating feeding device for feeding the blanks one at a time from the lower part of the blank receptacle onto the 85 platen, a reciprocating feeding device adapted to feed the slugs one at a time from said hopper through the guideway, and mechanism for actuating the main printing device so as to print the same subject matter on the 90 upper face of each of the cards, and for actuating the slug lifting device so as to raise the slugs successively to the blanks as the slugs are fed one at a time over said slug lifting device, and print on the lower faces 95 of the cards, and means for inking the upper surface of said slugs, separate means for inking the main printing device, and a device for retaining the slugs in succession in printing position on said slug lifting device 100 while passing through the opening in said platen.

In testimony whereof, I hereunto affix my signature in the presence of two witnesses.

WALTER HAY.
